UNITED STATES PATENT OFFICE

EMMANUEL G. KONTOS, OF CHICAGO, ILLINOIS

WING

Application filed December 18, 1930. Serial No. 503,153.

The invention relates to improvements in flying machines and particularly to improved wings therefor.

An object of the invention is to provide improved wings for heavier-than-air flying machines with automatic stabilizing means.

Another object is to provide an improved wing applicable to any heavier-than-air flying machines, including propelled machines, 10 gliders, or toys.

Another object is to provide wings of the character referred to, with means formed on their under side to provide for carrying an increased amount of wing load.

Another object is to provide an improved wing with entering and trailing edges formed to increase stability thereof and minimize air resistance.

Another object is to provide a flying machine with means to prevent nose-diving, listing, tail-spinning, or inverted flying, without resorting to the use of either rudders, elevators, or ailerons.

Another object is to provide wings for a flying machine with improved means to neutralize the twisting force of the propeller which tends to overcome the stability of the machine and cause it to list.

The foregoing and such other objects of the invention as will appear hereinafter as the description proceeds, will be more readily understood from a perusal of the following specification, reference being had to the accompanying drawing, in which:

Fig. 1 is a plan view of the improved wavy wings.

Fig. 2 is a bottom view of the wings shown in Fig. 1.

Fig. 3 is an enlarged transverse sectional view of the wings, taken on line 3-3 of Fig. 1.

Fig. 4 is an enlarged fragmentary longitudinal sectional view, taken on line 4-4 of Fig. 1.

Fig. 5 is a bottom view, showing a wing having its leading and trailing edges tapering longitudinally towards the tip.

Fig. 6 is a fragmentary bottom view of 50 the tip of a modified form of wing.

Fig. 7 is a transverse view similar to Fig. 3, showing a wing of single thickness.

Fig. 8 is a plan view similar to Fig. 1, showing ailerons or elevators attached to the improved wing.

Fig. 9 is a transverse sectional view, in perspective, of the tip of a modified form of wing.

Fig. 10 is a diagrammatic view, illustrating the application of the improved wings to a dihedral monoplane.

Fig. 11 is a view similar to Fig. 10, illustrating another application of the improved wings.

In known types of power propelled heavier-than-air flying machines equilibrium and stability are maintained only by the employment and manipulation of ailerons, elevators, rudders, etc. Failure of any of these controlling elements to function properly may result in the machine slipping, nose-diving, or tail-spinning.

The improved wavy wing is so formed on its under surface that stability is automatically attained and held without manipulation of ailerons, elevators, or rudders, said elements being employed only to change the course of the flying machine from the horizontal. The improved form of wing may be applied to any known type of power driven flying machine, such as for example, dihedral planes, monoplanes, biplanes, or triplanes. It also may be applied to gliders, either of the commercial type or toys, and to toy miniature flying machines employing rubber band motors, or the like.

The improved wings preferably are continuous from tip to tip, as illustrated in Figs. 1, 2, 5, and 8, with the tips formed round, as shown. The wing structure preferably consists of the usual spars 11 and ribs 12 having a suitable covering 13, secured thereover, such as for example, fabric or metal. The upper side of the wings may be of any approved practical shape, having its leading and trailing edges 15 and 16, respectively, and tips 17 uniformly tapering downwardly to reduce air resistance. The under side of the wings is cambered longitudinally on each side of the longitudinal center,

preferably intermediate the tips, said cambers extending around the curved tips of the wings, as illustrated in Fig. 2, to provide substantially a continuous loop. Cambering the wings in this manner leaves a longitudinal central belly 18 stopping short of the tips.

Upon reference to Figs. 3 and 4, it will be noted that the belly 18 projects a short distance below the bottom face 19 of the leading and trailing edges 15 and 16, and the tips 17. The exact extent of projection of the belly 18, relative to the bottom face 19, may vary, depending upon the particular application of the wings because, for example, its application to a speed plane necessitates a smaller belly than when applied to slow flying planes.

The principle of forming the under side 20 of the wings as described, involves the utilization of the air current for stabilizing the flying machine. Air currents entering beneath the wings along the elevated leading edge 15 naturally swing upwardly into the forward longitudinal camber, striking the downwardly curved belly 18 of said wing. As the air currents continue rearwardly beneath the belly 18, they enter into the rear camber and pass out beneath the elevated trailing edge 16. This movement of the air currents insures an equal lifting force acting on each side of the longitudinal center of the wings, thereby balancing said wings on the longitudinal center.

Irrespective of any temporary position of the wings relative to the horizontal, said wings, and likewise the flying machine attached thereto, immediately tend to assume a horizontal position. To vary the course of the flying machine, ailerons or elevators 21, shown in Fig. 8, are provided on the trailing edge of the wings one adjacent each tip. These ailerons preferably extend partly around the respective tips of the wings to 45 maintain the smooth stream line. The usual rudder and elevators (not shown) are employed for controlling the course of flight. Since the improved wings insure automatic horizontal, longitudinal, and lateral stability, failure of the controls to operate the ailerons, rudder, or elevators, merely prevents bringing the plane out of the horizontal. A flying machine provided with wings of the improved character cannot nose-dive, tail-spin, or slip, due to the perfect equilibrium insured the plane by said improved wings.

The improved wing construction is readily applicable to dihedral wings and, in such application, as shown in Figs. 5 and 11, it is desirable, but not necessary, that the entering and trailing edges 15 and 16 of the wings taper inwardly towards each rounded tip. This wing formation minimizes the air resistance offered by dihedral wings. As illus-

trated in Fig. 6, the double cambered under side of the wings 22 may extend to the rounded tip without curving therearound.

Where a flying machine of extreme lightness is required, as for example, in scout planes or gliders, wings 23 (Fig. 7) of single thickness may be provided. The double cambered under surface of this style of wing may be identical with either of the wings hereinbefore described; however, no top covering or stream line effect is provided. Wings of the type shown in Fig. 7 are applicable for attachment on toys, because they may be stamped or pressed from metal or cardboard and readily secured to a miniature fuselage.

Although wings of the various types previously described are applicable to most commonly used forms of flying machines, wings 24, such as illustrated in Fig. 9, having a plurality of waves on the under side also may satisfactorily be employed. The fragment of the wing shown is provided with a depressed longitudinal center 25, intermediate depressed portions 26 one on each side of the longitudinal center, and depressed edges 27. The bottom plane of the depressed portions 26 is disposed a short distance above the plane of the depressed center 25, and the plane of edges 27 terminates above the plane of portions 26. The intermediate raised portions 28 and 29 preferably are in a common plane, thus providing a wing having a plurality of longitudinally extending air pockets on its under side. A wing of the type shown in Fig. 9 may be used on toys, 100 gliders, or darts, or a circular wing having its diametrical section the same as the transverse section of the wing shown may be provided.

It can readily be understood that air currents pass below and strike the under side of any of the types of wings shown, with substantially an equal force and velocity on each side of the longitudinal center, thus preventing listing, tail-spinning, and nose-diving. Since the air currents are equally distributed, the equilibrium and the stability of the flying machine are maintained without the use of a rudder or ailerons.

Heretofore, it has been necessary to tilt or elevate one wing of a flying machine slightly above the other to overcome the torsional strain of a single propeller. Such torsional strain tends to tilt a flying machine and direct it from its true course. This tendency to tilt and misdirect is overcome automatically by employment of the improved wings due to the particular formation of their under side.

Although exemplary forms of the improved wings have been shown in the accompanying drawing and described in detail in the foregoing specification, it is to be understood that the wing structure may embody certain modifications in detail without departing

from the spirit of the invention or the scope of the appended claims.

I claim:

- 5 1. A substantially rectangular wing, for a flying machine, having a downwardly flared edge therearound, and means formed in said wing, extending longitudinally thereof below the plane of said edge, to maintain the stability of said wing.
- 10 2. A wing for a flying machine, comprising in combination, a frame built of spars and ribs having its marginal edges turned downwardly and a longitudinal enlarged central portion, a covering for said frame, said covering conforming to the shape of said frame to provide a self-balancing wing.
- 15 3. A substantially rectangular wing rounded on its ends having a continuous downwardly curved marginal edge, and means formed in said wing extending longitudinally thereof below the plane of said edge to maintain the stability of said wing.
- 20 4. A substantially rectangular supporting plane having rounded ends comprising, in combination, a substantially flat top surface having its marginal edges curved downwardly, a central longitudinal rib on the under surface of said supporting surface, said rib merging gradually into longitudinal recesses formed in the under surface, and said recesses merging with the respective downwardly turned edges at a point above the bottom plane of said rib.
- 25 5. A substantially rectangular supporting plane having round ends comprising, in combination, downwardly curved marginal edges surrounding said plane, and a central longitudinal rib on the under surface of said plane merging with longitudinal recesses formed on said under surface between said rib and said curved marginal edges.
- 30 6. A substantially rectangular supporting plane having round ends, comprising, in combination, downwardly curved marginal edges surrounding said plane, and a central longitudinal rib terminating short of the ends on the under surface of said plane merging gradually with a recess extending therearound between said rib and the downwardly curved marginal edges.
- 35 7. A substantially rectangular supporting plane having its marginal edges curved downwardly providing a continuous inclined flange therearound, and means formed in the under surface of said plane and extending longitudinally thereof to equalize the effective lifting force on said wing on each side of the longitudinal center thereof.
- 40 8. A substantially rectangular wing for flying machines, having its ends rounded, comprising, in combination, a downwardly turned portion surrounding said wing, and a centrally arranged longitudinal, depressed portion on the under surface of said wing form-

ing air pockets of equal capacity thereunder, one on each side of said central portion.

9. In a supporting plane, the combination of, downwardly turned marginal edges surrounding said plane, a depressed central portion in said plane extending below the plane of said marginal edges, and the portion of said plane between said central depressed portion and said marginal edges being depressed to provide air pockets one on each side of said last mentioned depressed portion for stabilizing said plane.

In testimony whereof I affix my signature at 10 South La Salle Street, Chicago, Illinois.

EMMANUEL G. KONTOS.
